United States Patent Office

Des. 225,288
Patented Nov. 28, 1972

225,288

SIGN

James D. Dowsett, 403 Plymouth Drive,
Davison, Mich. 48423

Filed Nov. 27, 1970, Ser. No. 26,200

Term of patent 14 years

Int. Cl. D20—03

U.S. Cl. D96—12

Fig. 1

Fig. 2

Fig. 3

Fig. 4

Fig. 5

FIG. 1 is a front elevational view of a sign showing my new design.

FIG. 2 is a rear elevational view thereof.

FIG. 3 is a side elevational view thereof.

FIG. 4 is a top plan view thereof.

FIG. 5 is a bottom plan view thereof.

The broken line representation of indicia in FIG. 1 is for purposes of illustration only.

I claim:

The ornamental design for a sign, as shown and described.
